WATERCRAFT

John V. Golden, Stamford, Conn.

Application April 27, 1942, Serial No. 440,613

2 Claims.

(Cl. 114—67)

This invention relates to watercraft and has for its major object the provision of means for overcoming the resistance to movement of said craft through the water.

Another object of the invention is to provide a surface on the water for the watercraft whereby said craft is driven or caused to ride on said surface.

A further object is to provide means in the form of an endless surface which is unfolded progressively and over which the craft progresses overcoming water resistance and thus yielding increased speed with the use of less power.

Other features of the invention are to provide novel propulsion means and novel steering and elevating means to assist the craft in the movement through and over the water.

The foregoing objects and features and others which will become hereinafter apparent are realized in the structure shown in the accompanying drawing which is described in detail in the following specification. The illustrated form of the invention is intended as exemplary only of the invention which may be incorporated in various other ways.

In the drawing:

Fig. 1 is a side elevational view of a watercraft incorporating features of the invention.

Fig. 2 is a cross-sectional view as taken in the planes of the line 2—2 of Fig. 1.

Fig. 3 is a fragmentary detail rear view of novel elevator means.

Fig. 4 is a similar view of novel propeller means.

Fig. 5 is a fragmentary detail, partly in section, of the mounting of the rudder elevator shaft shown in Fig. 1.

The herein-contemplated craft may be provided with a hull 5 preferably made with a flat bottom 6. The prow 7 of the craft formed in the usual manner and in addition, may be provided with a fin 8 to act as a stabilizer to prevent side slipping. The stern 9 may be conventional.

According to the invention, the hull may be provided with lateral depending skirt portions 10 enclosing a chassis 11 which may be formed of angle members 12. Each of these members extend for an appreciable length along the sides of the craft as best seen in Fig. 1.

At each end of the chassis 11 is arranged a free running roller 13 and 14 respectively fore and aft, and about these rollers is trained a member in the form of a belt 15. Smaller rollers

16 may be provided between the rollers 13 and 14 to form supports to carry the weight of the craft on the lower "run" of the belt 15. Still smaller rollers 17 are used to support and prevent sagging of the upper "run" of said belt. As can be understood, all of the rollers are mounted on anti-friction bearings, as shown at 18.

The belt 15 is preferably made the full width of the craft (Fig. 2). In this instance, it is shown as extending from side to side of the craft between the chassis angles 12. Anti-slip means may be provided on the belt as by fastening transversely disposed fins or vanes such as the angles 19 on said belt.

Rollers 13, 14 and 16 are all free and allow the surface of the belt to be freely applied to the surface of the water.

Means may be provided to take up slack on the belt 15 to maintain the bottom "run" thereof taut. To this end, means such as the screw 29 may be arranged to adjust the position of the bearings of one of the rollers such as the aft roller 14.

It should be evident from the foregoing that, as the belt is free to move, the craft moves thereover in the manner of a surface vehicle, the craft, in effect laying its own smooth roadway, the principles involved being based on the reluctance of

30 a large flat surface, sinking when it is dropped flat on the surface of the water. Thus the craft tends to plane and increased buoyancy is imparted to the craft which rides along upon its flat surfaced belt. The fins or cleats 19 prevent 35 slipping of the belt on the surface of the water, and hold the belt on the water as the craft passes over, as can be understood. The dot and dash line W shown on Figs. 1 and 2 indicates the waterline when the boat is moving at its maximum speed.

The craft is propelled by propeller 21, which, as shown, comprises a plurality of helices 22 enclosed in a horizontal circular housing 23. The helices may be quite long, as seen in Fig. 1. This 45 propeller may be driven by a shaft 22^a from the mentioned power plant and is quite efficient because of its structure.

The rudder 24, placed at the front in this instance, may be combined with an elevator 25 and carried by a post 26 journaled in a tilting member 38 which has horizontal trunnions 41 journaled in supports 40. The member 38 is provided with a counterbore 39 to accommodate the enlarged shouldered portion 37 of the post 55 26, the upper end of which carries the tiller 42.

It will thus be seen that the post 26 is adapted to be both oscillated in a horizontal plane and tilted transversely, as indicated by the arrows 27 and 28. This elevator is utilized to raise the craft's prow during its initial movement, serving to hydroplane the craft out of the water, as can be understood.

In order to aid steering the craft at high speeds normally retracted baffles 30 may be provided; said baffles may be placed at the sides of the hull near the stern. When it is desired to turn to the right, the right or starboard baffle is dropped to the position shown by the dot-dash lines (Fig. 1). Left steering is obtained by dropping the left or port baffle.

While the rudder and elevators have been shown as located at the front of the craft and the propeller at the stern, it will be obvious that their respective locations may be reversed.

It should be understood that endless free running belts may also be used on the vertical sides of a boat in which case they would extend in width from the waterline downwardly, and in length from the bow to at least the widest portion of the boat, and when so used these belts would tend to overcome the resistance of the water against the front and sides of the boat.

As can be understood, the invention as exemplified in the following claims, may be practiced

in various other ways without departing from the true spirit and scope of the invention.

I claim:

1. A watercraft comprising a hull, an endless free moving belt carried beneath said hull, a propeller, and combined rudder and elevator means located at the front of the craft and connected to a tiller, whereby said craft is propelled substantially on the surface of a liquid medium, said combined rudder and elevator means being carried on a shaft which is universally mounted so that the tiller may serve to move the rudder and the elevator simultaneously.

2. A watercraft comprising a hull, a chassis carried beneath said hull, a plurality of free running support members mounted on said chassis, an endless belt supported by said support members, a plurality of anti-slip members on said belt, and a propeller extending below the anti-slip members on the belt and a combined rudder and elevator means located at the front of the craft said means comprising a post carrying on its lower end said rudder elevator, and on its upper end a tiller, said post being universally mounted intermediate its ends so that the tiller may serve to move the rudder and the elevator whereby the craft is steered and guided toward the surface of the water.

JOHN V. GOLDEN.
